PNEUMATIC DISPATCH TUBE APPARATUS

Filed Sept. 14, 1927

Patented Mar. 12, 1929.

1,704,836

UNITED STATES PATENT OFFICE.

PETER OLSON, OF OAK PARK, ILLINOIS, ASSIGNOR TO SAMUEL OLSON & COMPANY, OF CHICAGO, ILLINOIS, A CORPORATION OF ILLINOIS.

PNEUMATIC-DISPATCH-TUBE APPARATUS.

Application filed September 14, 1927. Serial No. 219,465.

This invention relates to improvements in pneumatic dispatch tube apparatus and particularly to the type in which a minimum flow of air is maintained through the transmission tube when no carriers are in transit, while means is provided for increasing the flow automatically upon the introduction of the carrier into the transmission tube. The purpose of the invention is to provide a relatively simple and dependable apparatus for automatically controlling the flow of air in the transmission tube as needed and it consists of certain features and elements of construction in combination as herein shown and described and as indicated by the claims.

In the drawings:

Figure 1 is a somewhat diagrammatic view of one complete circuit of a pneumatic dispatch tube system to which this invention is applicable.

Figure 2 is a vertical section of the valve controlling apparatus taken substantially at the axis of the tube and through the axes of the pneumatic devices which constitute it.

Referring first to Figure 1 there is shown at A a tank or reservoir which may be considered as a source of suction for the purposes of the invention. It may be understood that a suitable air pressure or suction pump will be connected with this reservoir for producing the reduced pressure in the tank, A. A suction supply pipe, B leads from the tank, A, through a valve casing, C, to the connecting pipe, D, which affords communication with the transmission tube of the system. This consists of two runs of tubing indicated at E and E¹, constituting outgoing and returning paths for carriers between the two stations, F and G. At the station, F, the tubes, E and E¹, are connected by a coupling, H, which is normally airtight, having a spring door, H¹, which is opened temporarily for introduction of a carrier to be transmitted from F to G. At station, G, the carriers are introduced at the mouth, J, of the tube, E¹, and are discharged past a spring door, K, at the station, F. As thus far described, the system is typical of those in common use; my invention relates to the mechanism associated with the valve in the casing, C.

Communication between the suction tube, B, and the connecting tube, D, is controlled principally by a valve, 1, which is normally closed when there are no carriers in transit

in the tubes, E and E¹. But at such times a partial or restricted flow of air is maintained through ports, 2 and 3, formed in the partition wall of the casing, C. A pneumatic device comprising a diaphragm, 4, is arranged adjoining the casing, C, and is in constant communication with the suction tube, B, through an opening, 5, at the center of the pneumatic chamber, 6. A rod, 7, extends through the opening, 5, from the diaphragm, 4, to the valve, 1, to serve as an operative connection from the diaphragm to the valve. The partial vacuum maintained in the tube, B, is normally communicated to both sides of the diaphragm, 4, through a by-pass, 8, with ports, 9 and 10, leading to the chambers, 6 and 11, at opposite sides of the diaphragm respectively. An atmosphere vent port for the chamber, 11, is controlled by a valve, 12, and it will be apparent that when this valve is opened the atmospheric pressure admitted to the chamber, 11, being greater than the pressure maintained in the chamber, 6, will force the diaphragm, 4, in the direction of opening the valve, 1. This opening of the valve, 1, is desired when a carrier is placed in either line, E, or E¹, of the transmission tube so that full suction may be applied to the carrier for moving it as rapidly as possible from one station to the other. To secure the opening of the valve, 1, whenever a carrier is placed in the transmission tube, I provide a second pneumatic device comprising a diaphragm, 14, which separates chambers, 15 and 16, the former being constantly subject to atmospheric pressure through ports, 17, in its wall. The other chamber, 16, communicates through a tube, 18, with the transmission tubes by way of the connecting pipe, D, into which it leads directly. This places the chamber, 16, under substantially the same pressure which exists in the transmission tube and, as previously explained, a partial flow of air is maintained through the transmission tube by way of the ports, 2 and 3, in the partition of the valve casing, C. Upon introduction of a carrier into the transmission tube, this partial or minimum flow of air is temporarily choked and the pull of the suction through the tube, B, produces a higher vacuum in the transmission tubes and connecting tube, D, which reacts in the chamber, 16, to move the diaphragm, 14, in opposition to its spring, 19. The rod, 20, which is rigidly attached to the diaphragm, 14, at

its center, is thus shifted in the direction for encounter of its abutment, 21, with the arm, 22, of a bell crank lever, 23, fulcrumed in a bracket, 24, which is shown supported on the 5 casing of the first pneumatic device. The lever, 23, connects through a link, 25, with a lever arm, 26, which carries the valve, 12, so that this linkage and the second pneumatic 10 with its diaphragm, 14, constitutes a trip device for admitting atmospheric pressure to one side of the diaphragm, 4, when a carrier is entered in the transmission tube, E, E¹. As already explained, this venting of the 15 pneumatic chamber, 11, causes the diaphragm, 4, to force open the valve, 1, and thus admit to the transmission tube the full force of the suction from the source, A.

As soon as the valve, 1, is opened the temporarily high vacuum in the passage, D, will 20 be somewhat relieved and the pressure in tube, 18, and chamber, 16, will consequently rise and allow the diaphragm, 14, to move back to normal position as shown in Figure 2. The exact pressure condition under which this will 25 occur will be determined by the pressure exerted by the spring, 19, which may be adjusted to the desired amount by the screw, 27. The abutment, 21, is preferably formed by the under side of the rounded head, 28, of 30 the rod, 20, and one side of the lever arm, 22, is beveled at 29 for encounter with the rounded side of the head, 28, as the rod, 20, returns to normal position. An open slot, 30, in the pivot connection between the link, 25 and lever, 26, and a spring, 31, stretched between the lever, 26, and one arm of the lever, 23, permits the bell crank lever to yield momentarily as the head of the rod, 20, passes it. The pneumatic of the trip device is thus reset 40 almost immediately after opening of the valve, 1.

The atmosphere vent valve, 12, also returns 45 promptly to its normally closed position under the influence of gravity, though a spring might be substituted to perform this work. The weight of the parts may be nearly balanced by a counterweight, 32, on the lever, 26, so as to make them readily operable by the diaphragm, 14, but they will be slightly overbalanced in the direction for closing the 50 valve, 12. As soon as the valve, 12, has closed the suction acting through the by-pass, 8, and the port, 10, begins to reduce the pressure in the chamber, 11, and this reduction continues 55 until the pressures in the chambers, 11 and 4, are again equal,—the time required for this equalization being determined by means of a regulating needle valve, 33, whose screw-threaded stem, 34, is carried in a bushing, 35, 60 screwed into an enlarged opening, 36, in the base of the pneumatic casing and concentric with the passage, 8. The adjustment of the valve, 33, is maintained by a lock nut, 37, abutting the bushing, 35. The exposed portion 65 of the bushing at 38 may be made non-

circular so that by unscrewing the bushing the needle valve may be removed with the bushing and without disturbing its adjustment therein in order to permit cleaning out the by-pass, 8, and its ports, 9 and 10, if any accumulation of 70 dust therein should interfere with proper timing of the mechanism.

As the pressures in chambers, 6 and 11, approach equalization the compressed spring, 40, reacting against the valve, 1, and diaphragm, 4, will force the valve back to closed position and if the timing valve, 33, has been properly adjusted, this will usually occur just as the carrier is discharged at its destination. If the valve, 1, should close before the carrier 80 has traveled to the point of discharge, the continued presence of the carrier in the transmission tube will again choke the tube so as to produce a momentarily high vacuum which will react again through the connection, 18, 85 and diaphragm, 14, to trip open the vent valve, 12, and again actuate the diaphragm, 4, for opening the suction valve, 1. Likewise, if a second carrier is introduced into the transmission tube before the first one has been discharged, the momentarily high vacuum will be again produced immediately upon closing of the valve, 1, and the valve will be re-opened as just described so as to apply full 90 force to the suction for drawing the second 95 carrier through the transmission tube. In other words, the vent valve, 12, will be tripped repeatedly as long as there is any carrier in the transmission tube of the system, although the closing of the valve, 1, may cause the 100 progress of the carrier to be momentarily retarded.

It will be understood that in a complete system each circuit such as that represented by the tubes, E and E¹, will be provided with its 105 valve-controlling mechanism of the character shown in Figure 2 so that the timing needle valve, 33, of each such mechanism may be adjusted to correspond approximately with the length of the particular circuit which it 110 serves.

I claim:—

1. A pneumatic dispatch apparatus comprising a transmission tube and a source of suction with a normally closed valve interposed between them and a pneumatic for operating said valve normally exposed to the suction at both sides; a by-pass associated with said pneumatic to permit equalization of pressures at its opposite sides and a regulating needle valve in said by-pass comprising a pointed screw, an internally and exteriorly threaded bushing set in the casing of the pneumatic and in which the screw is threaded, and a lock nut on the screw abutting the bushing for holding the screw at any adjusted position whereby the screw and bushing may be removed bodily and then re-placed without disturbing the adjustment 125 of the screw.

2. In a pneumatic dispatch apparatus, a control device comprising a pneumatic motor including a casing having two chambers with a pressure responsive element separating them, a by-pass connecting said chambers for equalization of pressures between them and a regulating needle valve in said by-pass comprising a pointed screw, a bushing in which said screw is threaded for adjustment, a lock nut on the screw abutting the bushing for maintaining adjustment, the bushing being removably secured to the casing of the pneumatic motor device to permit bodily removal and replacement of the screw without disturbing its adjustment. 10
